CLAIM

The ornamental design for a pair of shaving aid elements for a razor unit, as shown and described.

DESCRIPTION

FIG. 1 is a perspective view of a pair of multiple shaving aid elements for a razor unit, the elements illustrated in broken lines being shown for illustrative purposes only and forming no part of the claimed design; and, FIG. 2 is a front view of the multiple shaving aid elements of FIG. 1.

The surface(s) or portion(s) of the article not shown in the drawing or described in the specification form(s) no part of the claimed design.
